JAR CAP WRENCH

Filed July 12, 1932

UNITED STATES PATENT OFFICE

WILLIAM JACKSON ADAMS, OF KNOXVILLE, TENNESSEE

JAR CAP WRENCH

Application filed July 12, 1932. Serial No. 622,159.

This invention relates to devices for removing lids or caps from jars and particularly to a wrench for this purpose which will clamp upon the jar cap or lid and wherein by jar caps or lids which are difficult to remove may be readily removed.

The general object of the invention is to provide a very simple, easily operated and effective wrench of this character which is so constructed that the cap or lid is clamped uniformly at all points so that power may be applied to rotate the lid without the lid being mashed or injured and which further removes all chance of crushing the glass neck of the jar.

A further object is to provide a device of this kind which is adjustable so that the two jaws of the wrench may be adjusted within a relatively wide range of different sized jars, and another object is to provide a wrench of this character having the jaws so formed that the jaws on one side of the wrench will engage a relatively large cap or lid while the same jaws on the other face of the wrench will engage a relatively small lid.

Other objects will appear in the course of the following description.

My invention is illustrated in the accompanying drawing, wherein:—

Figure 1 is a plan view partly broken away of my improved wrench;

Figure 2 is a like view to Figure 1 but on a smaller scale showing the wrench closed and showing exaggeratedly the bolt deflected by the closing action;

Figure 3 is a section on the line 3—3 of Figure 1;

Figure 4 is a like view to Figure 3, Figures 3 and 4 both showing in dotted lines the jar and cap.

Referring to the drawing, it will be seen that my improved lid wrench comprises two sections 10 and 11, these sections being alike. Each of these sections is formed with a semi-circular jaw 12 in the head portion 13 of the wrench and with a handle 14. The handle of one section of the wrench mates with the handle of the other section so as to constitute a single handle whereby the wrench may be manipulated. Extending

through the head of each section of the wrench is an aperture 15 and extending transversely through these aligned apertures is a bolt 16 having a head at one end and a nut and washer at the other. By turning the nut off or outward, the jaws may be spread apart and by turning the nut inward, the jaws may be narrowed. The apertures 15 for the passage of the bolt are larger than the bolt itself so that the sections are in a way hinged with reference to each other, that is, they will rock upon the bolt so as to permit the handle sections to be spread apart for the application of the wrench upon a jar cap.

As shown in Figure 1, one face of the wrench is rabbetted so as to provide a lid engaging surface 17 of relatively large diameter on one face of the wrench and a lid engaging surface 18 of relatively smaller diameter on the other face of the wrench. Thus the nut 16a may be set for ordinary standard jar caps or lids and left in this condition and the wrench will then be applicable to any ordinary jar, the bearing surface 17 being used for lids of one size while the bearing surface 18 which constitutes a wrench of smaller diameter being used for smaller caps. Preferably, though not necessarily, one of the handle sections is apertured at 19 and the other handle section is provided with a dowel pin 20 which fit loosely into the aperture 19 so that the two handle sections are held in apposition at all times and one handle section will not rotate upon the bolt out of proper alignment with the other handle section.

While by providing the bolt with a nut I can secure considerable range of adjustment for the wrench so that jar caps of larger than standard size may be engaged by the wrench, yet I do not wish to be limited to this as it is obvious that the nut might be held from rotation or the bolt be headed and the adjustment simply secured by the rocking of the sections upon the bolt. Thus the bolt acts as a hinge and also as a spring acting after the jaws have been closed to cause the opening of the jaws, the closing of

the jaws acting to flex this bolt to a certain extent.

My wrench fits snugly all the way around the jar lid or cap and engages the top of the lid which is the rigid portion of the lid, thereby not injuring the lid in any way and eliminating any danger of crushing the threaded part of the glass jar.

This applies not only to the ordinary fruit jar lids of standard size but to lids for peanut butter and pickle jars.

While I have illustrated certain details of construction and arrangements of parts, I do not wish to be limited thereto within the scope of the appended claims. While preferably the wrench will be made of wood, it is obvious that it might be made of other materials.

While I have heretofore referred to this hinge as being adapted for removing jar caps, it will, of course, be understood that it is equally adaptable to putting the jar caps in place or tightening the caps.

One of the advantages of my invention is that it is applicable not only to the ordinary Mason jar caps but also to the new style glass top fruit jar lid wherein the metal of the lid is cut away to expose a transparent glass disk within the top of the lid. With either of these styles of lid, the wrench engages the upper portion of the lid above the screw-threads thereof and cannot be brought down over the screw-threads as shown clearly in Figures 3 and 4 so that when pressure is applied to the handles of the wrench, the wrench will not crush the screw-threads or the cap itself or jam the cap on the jar or possibly break the mouth of the jar.

I claim:

40. 1. A jar cap wrench formed of two mating sections, each section having a head and a handle, the head of each section having a semi-circular recess formed therein, and mating with the semi-circular recess in the other head, the outer portions of the sections outward of the recesses having confronting faces, the outer portions of each section outward of the recesses being transversely bored from one side edge of the head to the other side edge thereof, and a bolt passing through said bore, the bolt holding the said confronting faces in close approximation to each other, and yieldingly holding the handles in divergent relation whereby as the handles are closed, the bolt will be bent.
50. 2. A jar cap wrench formed of two mating wooden sections, each of these sections having a head and a handle, the head of

each section having a semi-circular recess therein mating with the semi-circular recess in the other head, the heads of the two sections beyond the recesses being formed with alining bores, and a bolt passing through said bores and holding the confronting faces of the sections beyond the recesses in close approximation to each other, the handles of the sections being held in normally divergent relation by said bolt whereby as the handles are forced toward each other, the bolt will be bent, the resilience of the bolt acting to spread the sections apart when pressure on the handles is relieved.

3. A jar cap wrench formed of two mating wooden sections, each of these sections having a head and a handle, the head of each section having a semi-circular recess therein mating with the semi-circular recess in the other head, the heads of the two sections beyond the recesses being formed with alining bores, and a bolt passing through said bores and holding the confronting faces of the sections beyond the recesses in close approximation to each other, the handles of the sections being held in normally divergent relation by said bolt whereby as the handles are forced toward each other, the bolt will be bent, the resilience of the bolt acting to spread the sections apart when pressure on the handles is relieved, and a guide pin mounted in one of the handle sections, the other section having an opening into which the guide pin loosely fits.

4. A jar cap wrench formed of two mating sections of wood, each of these sections having a head and a handle, the head of each section having an approximately semi-circular recess formed therein mating with the recess in the other head, the outer ends of the sections beyond the recesses having alining bores, a transversely extending bolt passing through said bores, the bolt having a length slightly greater than the combined width of the two sections at their outer ends, the bolt holding the handles in normally divergent relation whereby as the handles are closed the bolt will be bent, the resilience of the bolt acting to open the wrench, a guide pin mounted in one of the handle sections, the other handle section having an opening into which the guide pin loosely fits, the bolt preventing the opening of the sections to an extent where said guide pin will leave the opening into which it fits.

WILLIAM JACKSON ADAMS.
